REINFORCED CONCRETE SLAB AND CORE
THEREFOR

Arthur M. Bowman and James I. Bowman, Pittsburgh, Pa.; said Arthur M. Bowman assignor to said James I. Bowman

Application March 15, 1932, Serial No. 598,913

12 Claims. (Cl. 72—66)

Our invention relates to a poured reenforced concrete slab construction and to an improved form of hollow sheet metal core adapted to be incorporated in such construction.

5 It has been proposed heretofore to lighten poured reenforced floors by placing hollow cores of tile or sheet metal upon forms, before pouring the concrete thereon. All types of such cores with which we are familiar, however, are characterized by numerous objections. Tile cores are costly, fragile and heavy, and require considerable labor to place them in position. Sheet metal cores as heretofore constructed (as shown in the Walker Patent No. 1,101,767) have been made in 10 short sections of a number of pieces which require bolting together, and each core was supported from the form by individual means independent of all the other cores.

The supports for the cores were nailed to the 20 forms and when the latter were removed after setting of the concrete, the nails protruded from the lower surface of the floor and the feet of the supports were exposed, marring the appearance of the ceiling. It was necessary to plaster the 25 lower surface of such floor after first clipping the protruding nails, in order to provide a satisfactory surface therefor. The shape of the cylindrical cores, furthermore, did not distribute the concrete section to the best advantage.

30 It is an object of our invention therefore to improve upon known types of hollow cores for use in the construction of poured reenforced concrete slabs and particularly to provide floors which have a continuous lower concrete surface in one 35 plane.

In accordance with our invention, we form 40 hollow cores of corrugated sheet metal. Each core comprises a body portion and a separate removable cover. The body portion may have a flat bottom, vertical sides, and inclined walls connecting the bottom and sides, or the flat bottom may be omitted and the inclined walls exclusively 45 constitute the bottom of the core. The cover is substantially flat with depending flanges for fitting over the vertical sides of the body portion of the core. The cores are supported above the forms by preformed wire chairs which may readily be secured thereto and also serve the purpose of securing the body portion and cover rigidly together 50 preventing distortion of the core during the construction operations. The chairs have rounded feet so that the concrete when poured flows around under the feet and forms a uniform unmarked lower surface for the floor since the 55 chair feet have substantially only point contact

with the form. A liner within the form aids in the production of a smooth lower surface for the floor. The cores are spaced one from the other by stirrup rods extending over a plurality of cores and having depending portions lying between adjacent cores. The depending portions of the stirrup rods also serve to support reenforcing bars between the cores. 5

When the cores, stirrup rods and reenforcing bars have been placed in position, the result is 10 a fabric or mat of metal members for receiving the concrete. The weight of the bars and rods in the mat prevents floating of the cores and the entire metal fabric is a unitary whole.

For a complete understanding of the invention, 15 reference is made to the accompanying drawing illustrating the present preferred embodiments. In the drawing:

Figure 1 is a side elevation of a core made according to our invention having supporting chairs 20 associated therewith;

Figure 2 is an end view of the core as shown in Figure 1;

Figure 3 is a partial perspective view of the cover; 25

Figure 4 is a similar view of the body portion;

Figure 5 is a transverse sectional view taken through a floor in which our cores are incorporated;

Figure 6 is an elevation of a modified form of 30 chair;

Figure 7 illustrates a partial modification of the preferred form of chair; and

Figure 8 is a perspective view of an end stop for the core. 35

Referring in detail to the drawing, we form a core 10 having a body portion 11 and a cover 12 of corrugated sheet metal. The core may be made in any length, but we prefer some standard length such as eight feet, for example. 40

The body portion and cover of the cores may be readily assembled or separated since they are designed for a relatively loose fit. As will be apparent from the drawing, the body portion 11 comprises a bottom 13, vertical side walls 14, and 45 inclined portions 15 connecting the side walls to the bottom. Both the covers and the body portions of the cores may be bent to the desired shape readily in a break after corrugation. Both the covers and the body portion nest compactly 50 for shipment.

The body portion 11, instead of having a flat bottom 13, may be composed exclusively of the sides 14 and inclined portions 15 which extend to a common junction forming a V-shaped bot- 55

tom for the body portion. The Walker patent above referred to shows a modified form of core having a V-shaped bottom of the character mentioned. This shape of core may be desirable 5 in some instances and is characterized by all the advantages of the shape of core shown in the drawing.

When the nested covers and body portions of the cores have been delivered on the job, they 10 may be assembled quickly by placing the covers on the body portions. Preformed wire chairs 16 provide means for supporting the cores a short distance above the plane of a form indicated at 17, which determines the lower surface of 15 the floor, that is, the ceiling of the room below. The chairs are preferably shaped as shown in Figure 2, to conform to the shape of the cores and provide feet 18 for resting on a form 17. A tie wire 19 may be bent around the upstanding 20 ends 20 of the chairs 16 and said ends bent over as shown in Figure 2. The chairs are thereby secured firmly to the cores, and the covers and body portions of the cores are likewise secured to each other. Instead of having both ends of 25 the chair 16 extending vertically when applied to the core, one end may be bent over as at 20 during manufacture. This eliminates one bending operation performed on the job.

When installing the assembled cores preparatory to pouring, we prefer to employ stirrup rods 21 for spacing the cores from each other. The assembled cores and chairs are placed on the form 17, which may have a liner 22, in approximately the relative positions they are to 30 occupy in the finished floor. The stirrup rods are then placed over the cores for properly spacing and aligning the latter in their final position. Slight shifting of the cores relative to each other may be necessary for this operation. As will 35 be apparent in Figure 5, the stirrup rod is constituted by a plurality of downwardly extending U-shaped portions 23, connected by straight portions 23'. The straight portions 23' are designed to rest on the cores and the U-shaped portions 40 to hang therebetween. Reinforcing bars 24 are laid on the U-shaped portions 23 of the stirrup rods and the concrete may then be poured over the cores, stirrup rods and reinforcing bars. As before stated, the reinforcing bars, the stirrup 45 rods and the cores form a unitary mat, resting on the form, to be embedded in the concrete. Floating of the cores is prevented by the weight of the bars and rods. By vibrating the mat with a power hammer, the concrete flows entirely 50 around the cores and chairs to form a floor having a continuous, uniform, plane lower surface without any projections or blemishes. When the form has been removed, a finished surface is 55 found on the bottom of the floor slab which requires no further treatment to constitute a highly satisfactory ceiling except painting. The surface may be painted without any difficulty and the result is a smooth, finished ceiling.

Figure 6 illustrates a chair 25, which is of one-piece construction. One end of the chair has a 60 preformed eye 26. The other end is adapted to receive the eye 26 and to be bent downward as at 27 to bind the cover and body portions of the core together and to secure the chair thereto. The feet of the chair 25, instead of being bent 65 at acute angles as in the chair 16, extend horizontally as shown at 25a. Between the feet 25a is positioned an upwardly extending portion 26a for engagement with the bottom 13 of the core. The feet 25a provide a greater length of con-

tact with the form liner 22 than do the feet 18 of the chair 16, and thus avoid denting the liner when a heavy load is placed on the core assembly, as for example, by a workman stepping thereon.

Figure 7 illustrates a preformed tie rod 28 having eyes 29 at either end thereof which may be substituted for the wire tie rod 19 with twisted ends, shown in Figure 2. If the tie rod 28 is employed, it is merely dropped on the core so that the ends 20 of chair 16 enter the eyes 29 of 10 the rod. The ends 20 are then bent over as before described. If one end of the chair 16 is bent down in the manufacture, one eye of the eye rod must, of course, be slipped over the bent end and the entire rod then swung downwardly so 15 that the remaining eye engages the straight end of the chair which is then bent over.

Figure 8 illustrates a simple form of stop for the ends of the cores. In case it is not desired to extend the cores into abutment with the supporting beams, flow of concrete into the open 20 ends of the cores may be prevented by the use of a stop such as that shown at 30. The stop 30 comprises a flat plate of appropriate thickness having a flange 31 on one edge thereof. The 25 flange 31 is slit to provide tongues 32 and 33. Two of the tongues, for example the tongues 32, are bent slightly upward and the remaining tongue is bent down slightly. The plates are applied to the ends of the cores by placing them 30 adjacent the core ends so that the tongues 32 engage the top of the cover and the tongue 33 the lower surface thereof. A light blow with a hammer is sufficient to secure the stop plates frictionally to the cores to prevent the flow of 35 concrete thereinto.

The construction herein described is characterized by many advantages over the practice heretofore followed. By cross corrugating the body portions and covers of the cores, great rigidity 40 is imparted to the assembled unit. At the same time, the cores are light in weight and are relatively inexpensive. They may be made from sheet mill scrap. The savings in concrete effected by the use of the cores sometimes run as 45 high as 50%, with a substantial reduction in the cost of floor construction. The use of cores lightens the floor and permits the use of lighter weight supporting steel. The specific shape of the cores of our invention also gives rise to the 50 further advantage that the section of concrete is distributed to the greatest advantage. By using a liner in the form, the lower or ceiling surface of the floor is very smooth and may be painted without plastering. The appearance of 55 the lower surface, furthermore, is not marred by any projecting nails or chair feet exposed therein. The chairs support the cores at the proper distance above the lower surface of the floor and the stirrup rods properly position the reinforcing 60 bars. The assembly of cores, chairs, stirrup rods and reinforcing bars constitutes a unitary fabric over which concrete is poured. The unity of the fabric is such that the application of a vibrating 65 hammer to one portion thereof affects the vibration of the entire surrounding structure to settle the concrete therearound and the weight of the mat or fabric prevents flotation of the cores. The shape of the cores is such that concrete flows around them with little or no obstruction and a 70 smooth, plane, lower or ceiling surface is produced.

Many other practical advantages of the invention will be apparent. No nuts, screws, bolts or 75 nails are necessary. A short length of small bore

pipe is the only tool that is necessary for bending the upwardly extending ends of the chairs over to secure the covers on the body portions. The shape of the chair and the fact that it is drawn tightly around the core prevents distortion of the core and the shape and corrugation of the cores is a further safeguard against this defect. The chairs are relatively inexpensive to manufacture and provide substantial support for the cores as well as protection against distortion. The simplicity of the operations necessary to assemble and place the cores reduces the labor cost and renders the system highly practical for field use.

15 While the invention has been described as applied to floors cast in situ, it is equally well adapted to the manufacture of pre-cast slabs for general use, whether as floors, side-walls, bulkheads or the like.

20 Although we have described and illustrated herein a preferred embodiment of the invention, together with certain possible modifications thereof, it will be obvious that many changes in the described embodiment may be made without departing from the spirit of the invention or the scope of the appended claims.

We claim:

1. A core for reenforced concrete slabs, comprising a body portion having a bottom, side walls, and inclined walls connecting said bottom and side walls, a removable cover for said core, and means surrounding said core for supporting it and securing the cover and body portion together.
- 35 2. A core for concrete construction, comprising an open top channel, a substantially flat removable cover therefor, and means embracing said channel and cover for securing them together and supporting the core.
- 40 3. In a core for concrete slab construction, the combination with an open top channel having a removable cover, of a preformed wire chair for supporting said core, and a tie wire engaging said chair for securing the cover on the core.
- 45 4. A wire chair for supporting a core having a flat bottom, inclined and vertical walls, said chair comprising portions bent inwardly to engage the bottom and said inclined walls, and outwardly bent portions forming supporting feet.
- 50 5. A wire chair for supporting a core having a flat bottom, inclined bottom and vertical side walls, said chair comprising portions bent inwardly to engage the bottom and said inclined walls,

and outwardly bent, substantially horizontally extending portions forming supporting feet.

6. A core for reenforced concrete construction, comprising a body portion having substantially vertical sides and a bottom including inclined walls, and a removable cover adapted to be placed on said body portion, and a wire chair for securing the cover and body together and supporting the assembled parts.

7. In a concrete slab construction, the combination with a hollow, channel-shaped core having a removable, substantially flat top, of a preformed wire chair for bracing said core against distortion and supporting it above a form.

8. In a reenforced concrete slab construction, a core having a substantially flat top, substantially vertical walls and a substantially V-shaped bottom, means for supporting the core above the bottom of the slab prior to pouring concrete, and a monolithic layer of concrete extending above and below the core and having smooth top and bottom surfaces.

9. A core for concrete construction, comprising an open top channel and a substantially flat, removable cover therefor, and means for securing said parts together, said means having projections constituting supporting feet for the assembled core.

10. In a concrete slab construction, the combination with a hollow, channel-shaped core having a removable, substantially flat top, of means embracing the core for reenforcing it against distortion, said means having feet for supporting the core above a form deck.

11. A chair, for supporting a core having inclined bottom walls, substantially vertical side walls, and a top, said chair comprising a rod having outwardly bent portions forming supporting feet, re-entrant portions adapted to engage said inclined bottom walls and substantially straight portions adapted to engage said vertical sides and extend over said top.

12. In a floor in course of construction, a form and a mat thereon comprising a plurality of substantially flat-topped cores having tapering bottoms, spacing rods resting on the cores and reinforcing bars suspended on the rods, and means for supporting said mat above the form on feet rounded to receive concrete substantially entirely thereunder.

ARTHUR M. BOWMAN.
JAMES I. BOWMAN.
